United States Patent

Des. 240,640
Patented July 20, 1976

240,640

BURIAL VAULT LINER

Robert F. Clark, Rocky Mount, and Arlen G. Harris,
Winston-Salem, N.C., assignors to Electronic Data
Controls Corporation, Winston-Salem, N.C.

Filed Jan. 13, 1975, Ser. No. 540,324

Term of patent 14 years

Int. Cl. D31—00

U.S. Cl. D31—1

Fig. 2

Fig. 1

Fig. 4

Fig. 3

Fig. 5

Fig. 6

Fig. 7

Fig. 8

FIG. 1 is an exploded perspective view of a burial vault liner showing our new design;

FIG. 2 is a perspective view of the liner in assembled condition;

FIG. 3 is an exploded side elevational view thereof;

FIG. 4 is an exploded end elevational view;

FIG. 5 is a top plan view;

FIG. 6 is a bottom plan view of the lid;

FIG. 7 is a top plan view of the bottom section; and

FIG. 8 is a bottom plan view thereof.

We claim:

The ornamental design for a burial vault liner, as shown and described.
